SOUND CHAMBER FOR LOUD SPEAKERS

Vernon J. Richards and Charles D. Wright,
Crown Point, Ind.

Application July 21, 1958, Serial No. 51,858

Term of patent 14 years

(Cl. D26—14)

Fig. 1.

Fig. 2.

Fig. 1 is a side elevational view of a sound chamber for loud speakers, showing our new design, the appearance being substantially the same from all sides; and

Fig. 2 is a cross-sectional view, taken on line 2—2 in Fig. 1.

The broken line showing of a representative loud speaker in Fig. 1 is for illustrative purposes only.

We claim:

The ornamental design for a sound chamber for loud speakers, as shown and described.
